UNITED STATES PATENT OFFICE.

AUGUSTE JEAN LECOUTRE, OF WORCESTER, MASSACHUSETTS, ASSIGNOR TO ROYAL WORCESTER CORSET CO., OF WORCESTER, MASSACHUSETTS, A CORPORATION OF MASSACHUSETTS.

CORSET AND THE LIKE AND FASTENING SYSTEM THEREFOR.

1,381,651.

Specification of Letters Patent. Patented June 14, 1921.

Application filed March 28, 1918. Serial No. 225,221.

To all whom it may concern:

Be it known that I, AUGUSTE JEAN LECOUTRE, a citizen of the United States, residing at Worcester, in the county of Worcester and State of Massachusetts, have invented certain new and useful Improvements in Corsets and the like and Fastening Systems Therefor, of which the following is a specification.

10 My invention relates to corsets, corset waists, and abdominal belts, and similar articles, which have two front steels or clasps, which have fastening devices which attach the steels together. One of the steels has 15 the eye members thereon, and the other steel has the studs thereon, which are engaged by the eye members.

The object of my invention is to improve upon the construction of corsets, and similar 20 articles, which have two front steels with the fastening devices thereon above referred to, and more particularly to provide a locking device, made independent of the eye members, and studs on the steels, but combined therewith, and adapted to engage with the studs and prevent them from becoming accidentally detached or unfastened from the eye members.

My invention consists in certain novel 30 features of construction of my locking device for the fastening devices on the front steels of corsets, and similar articles.

In the ordinary construction of corsets, and similar articles, which have two front 35 steels, the studs on one of the steels extend loosely through the eye members on the other steel, and are liable to become accidentally detached from the eye members, when the corsets are in use, so that the steels 40 will unfasten.

In my improved construction of a corset, corset waist, abdominal belt, and similar articles, with front steels with fastening devices thereon, comprising eye members, and 45 studs, I provide a locking device for holding the studs in the eye members, and preventing them from becoming accidentally detached, to allow the steels to unfasten.

My locking device, comprises a flap or 50 strip, preferably of textile fabric, on the front of the corset, adjoining the front steels, which is stitched or otherwise secured along one edge to one side of the corset, preferably contiguous to the outer edge of the

steel having the eye members thereon. The 55 other edge of said flap or strip is free, and provided with snap fasteners or buttons, which snap over the heads of the studs on the other steel, and are detachably secured to said studs, to prevent them from coming 60 out of or being detached from the eye members, and allow the steels to unfasten when the corset is in use.

Referring to the drawing:

Figure 1 shows a front view of a corset 65 with my improvements combined therewith, and with the locking device in operative position.

Fig. 2 corresponds to Fig. 1, but shows the locking device detached at one edge, and 70 turned over, and

Fig. 3 shows the two front steels detached, and the locking device turned back.

The corset shown in the drawing may be of any ordinary construction, and in this instance consists of the two halves 1, having the hose supporters 2 attached to their lower edge. The two parts 1 are in this instance laced together at their rear portion, by lacing 3, and are provided with two steels 80 or clasps 4 at their front portion. One of the steels 4 has the eye members 4' thereon, and the other steel 4 has the studs 4'' thereon, in the usual and well known way. The studs 4'' are adapted to pass through the 85 eye members 4', to secure the two steels 4 together.

The above mentioned parts may be of any usual and well known construction.

I will now describe my improvements.

Upon the front of the corset is a flap or strip 5, which is preferably of textile material and of substantially the length of the corset, or it may be shorter, and of a width to extend over the two front steels 4. The 95 flap or strip 5 is attached along one edge to one side of the corset, contiguous to and along the side of the steel 4 carrying the eye members 4', by stitching 5', or otherwise.

Secured to the free edge of the flap or strip 5 are snap fasteners, or buttons 5'', which in this instance have the solid flat outer heads 5'''. The snap fasteners 5'' are adapted to extend over and engage the 105 studs 4'', when the two front steels 4 are secured together, as shown in the drawing. The engagement of the snap fasteners 5''

with the studs 4" prevent the studs from coming out of the eye members 4', and act as a lock to secure said studs in said eye members, and prevent the two steels from 5 becoming accidentally unclasped or unfastened when the corset is in use. The snap fasteners or buttons 5" are readily attached to the studs 4", and detached from said studs, when the corset is put on, and removed from 10 the wearer.

I have shown my snap fastener, or locking means for the front steels combined with a corset, but it will be understood they may be combined with a corset waist, or an 15 abdominal belt, or other similar article, in which two steels or clasps are used, having eye members and studs to secure the steels together.

It will be understood that the details of 20 construction of my improvements may be varied if desired.

Having thus described my invention, what I claim as new and desire to secure by Letters Patent is:

25 1. As an improved article of manufacture, a corset, or similar article, having two front steels, one carrying eye members of the key-hole slot type and the other carrying studs, and a supplemental flap or strip attached 30 to that side of the corset carrying the eye

members and provided with means to fit over the heads of the studs when engaged with the eye members and oppose relative movement of the studs and the eye members into disengaging position. 35

2. A fastener for corsets and the like including an eye member, a stud for engagement in said eye member, and a snap fastener socket adapted to snap over the head of the stud and to grip the stud after the stud 40 has been engaged with the eye member, said fastening means reducing the play between stud and eye member in a direction longitudinal of the stud, and said socket extending beyond the outer end of said stud. 45

3. In a corset or similar article, the combination with two front steels, one having keyhole slot eye members, and one having studs to secure them together, of a supplemental flap or strip attached to the corset 50 and provided with snap fastener sockets positioned on said flap or strip to engage over and grip the heads of said studs after engagement of said studs with said eye members, thereby to lock said studs in said eye 55 members.

AUGUSTE JEAN LECOUTRE.
